UNITED STATES PATENT OFFICE.

FRED A. TAYLOR, OF LOWELL, MASSACHUSETTS.

PENCIL-SHARPENER.

SPECIFICATION forming part of Letters Patent No. 437,873, dated October 7, 1890.

Application filed September 21, 1889. Serial No. 324,698. (No model.)

To all whom it may concern:

Be it known that I, FRED A. TAYLOR, a citizen of the United States, residing in the city of Lowell, in the county of Middlesex and 5 State of Massachusetts, have invented new and useful Improvements in Pencil-Sharpeners, of which the following is a specification.

My invention relates to improvements in pencil-sharpening machines in which the wood 10 is cut in the direction of its grain and the lead in the direction of its length; and the objects of my improvements are to make a machine which shall be small enough to be carried in the vest-pocket and at the same 15 time be durable and do its work with speed, neatness, and efficiency.

My invention consists more particularly of a holder made of spring-wire, which during 20 the process of sharpening grips the pencil firmly enough to prevent any forward movement, holds the pencil in its proper position in relation to the knife, and at the same time allows the pencil to rotate freely under the hand of the operator, so that every part of 25 the circumference of the pencil may be in turn presented to the cutting operation of the knife. The wire which forms the holder is extended into a projecting arm, at the end of which, by suitable bendings, is formed a bearing 30 for the support and movement of the knife. The knife is so attached to the projecting arm of the holder that it is capable of three movements—first, an oscillating movement forward as it forces its way through the wood and lead of the pencil which is to be 35 sharpened, and backward to renew the stroke; second, the cutting-edge may be raised or lowered at the will of the operator to such a degree as will best favor the true and even

40 cutting of the pencil, and, third, if it be desirable, the whole knife may be raised or lowered through a slight distance, and either or both of these two latter operations may take place during any part of the stroke and without 45 any pause in the operation. As one end of the wire forming the holder is extended into an arm for the support of the knife, so the other end of the wire is wound once loosely around this projecting arm as a support and 50 then is extended still farther to form a catch,

which securely confines the knife when it is not in use.

By reference to the accompanying drawings, Figure 1 is a side view of the spring-holder as it appears when at rest or not in use. Fig. 2 is a side view of the spring-holder as it appears when the pencil is inserted. Fig. 3 is a side view of the spring-holder, showing the projecting arm and bearing for the support of the knife. Fig. 4 is an end view of the spring-holder, showing the loose coil which helps to support and hold the projecting arm in its proper position, and also the catch designed to confine the knife when not in use. Fig. 5 is a top or plan view of the knife, showing the twist to form the handle and the hole by means of which it is attached to the projecting arm of the holder. Fig. 6 shows the knife attached to the projecting arm of the holder in position for use. Fig. 7 shows the position of the knife when not in use.

At A, Fig. 1, is shown the spring-holder, which is made by bending or distorting a coil-wire spring until it sets in some position other than that of a straight line, preferably in the shape of a crescent or segment of a circle.

At A, Fig. 2, is shown the spring-holder as it appears when a pencil has been inserted. The insertion of the pencil causes the holder to approximately assume the straight position 80 which was natural to it before it was bent or distorted, and now in its attempt to reassume its distorted shape it exerts a pressure upon the pencil and holds it firmly enough to prevent any forward movement during the process of sharpening, and at the same time permits the pencil to rotate, so that each part of its circumference may be in turn presented to the cutting action of the knife.

Every part of the machine except the knife 90 is made from one and the same piece of spring-wire, and at B, Fig. 3, is shown one end of the wire which forms the holder bent along the side of the holder and in a direction nearly parallel to it, where it forms, by means of suitable bends at its end, a support and bearing for the attachment and movement of the knife.

At a, Fig. 3, is shown the wire of the arm bent upon itself in such a way as to form a smooth and even support for the bottom of 100

the knife, and at E, Fig. 3, the wire is shown bent upward to pass through the hole in the knife, thus forming a bearing upon which the knife may oscillate, and at b, Fig. 3, the wire is shown bent downward to form a fastening to prevent the knife from coming off the wire.

By reference to E, Fig. 6, it will be seen that the length of the bearing E is greater than the thickness of the knife F, thus permitting a slight up-and-down movement of the whole knife, and the hole f in the knife, Fig. 6, is of greater diameter than that of the bearing E, by which it is attached to the projecting arm of the holder, and this fact permits the cutting-edge of the knife to be raised or lowered at the will of the operator. As has been shown, one end of the wire which forms the spring-holder is bent and extended into a projecting arm B, Fig. 6, for the support of the knife. The other end of the wire is wound loosely once around said projecting arm at C, Fig. 6, and is further extended upward and inward to form a catch D, Fig. 6, and D, Fig. 7, which securely confines the knife when not in use. The wire is wound around the projecting arm for the purpose of supporting it and giving it additional strength to resist the strain to which it is subjected under the action of the knife, and it is coiled loosely, so that when the spring-holder changes from its distorted shape into an approximately-straight line or back again, (as the pencil is inserted and withdrawn,) it (the supporting-coil) may slide along the arm and in no way restrict the elasticity of the holder A, but give it full play in every movement.

At F, Fig. 5, is shown the knife, which is made out of one piece of steel, twisted near the middle, so that one part, which thus forms a convenient handle, is at right angles to the other part which forms the blade. At the end of the blade farthest from the handle is the hole f, Fig. 5, by which the knife is attached to and may oscillate upon the bearing E, Fig. 6, the diameter of which is less than that of the hole in the knife. This method of construction gives a handle which is of good shape and easily made, and which cannot get out of order, and the hole being placed at the end of the knife gives the greatest possible amount of leverage in performing the required work, and there is less liability of the particles of lead soiling the fingers than there might be if the bearing came at some other part of the knife.

The operation of the machine is simple. The pencil G, Fig. 6, is pushed through the distorted coil-spring holder A, Fig. 6, until its point projects a little beyond the cutting-edge of the knife when the knife F, Fig. 6, is at right angles to the pencil G, Fig. 6. The insertion of the pencil straightens the distorted coil, which then in its effort to reassume its distorted shape exerts a sufficient pressure upon the pencil to prevent any forward movement under the action of the knife during the process of sharpening, but at the same time

permits the pencil to rotate freely under the hand of the operator. The knife, held in the right hand of the operator, is then sent forward, cutting through the wood and lead at the point of the pencil, and is then brought back to renew the stroke. The pencil, held in the left hand of the operator, is then rotated so as to bring another part of its circumference under the cutting action of the knife, and another stroke is taken, and this operation is repeated until the pencil has been sharpened to suit. It is obvious that the point can be made long or short, as is desired, and that the lead may be left round in shape, or may be sharpened on two sides only, leaving a flat point, such as is used against a ruler by draftsmen. When the pencil is inserted and the distorted coil-spring holder A, Fig. 2, is thus made to assume a straighter shape, the loose supporting-coil C, Fig. 6, slides along the projecting arm B a short distance, and thus does not in any way restrict the elasticity of the distorted coil-spring holder, and when the pencil is taken out the loose supporting-coil slides back again into its original position.

An essential feature of the machine, and hence of the operation, is the loose joint at E and f, Fig. 6, (where the knife is attached to the projecting arm of the holder,) which permits three different movements to the knife. The bearing E, Fig. 6, passed through the round hole f, Fig. 6, in the knife permits the knife to oscillate freely forward and backward over that part of the pencil which is to be cut, and the thickness of the knife being less than the length of the bearing E, to which it is attached, allows a slight upward and downward movement of the whole knife, if desirable, and the diameter of the hole f, Fig. 6, in the knife being greater than that of the bearing E permits the cutting-edge of the knife to be raised or lowered at the will of the operator, who may thus decide at what angle the knife shall enter the wood, and may change that angle during any part of the stroke. Thus it is obvious that the operation of sharpening may be completed by a few heavy strokes, taking thick shavings, or may be conducted with the utmost delicacy by taking light strokes and thin shavings, and without the slightest danger of breaking the lead.

I believe it to be broadly new in pencil-sharpening devices to hold the pencil in its position during the process of sharpening by means of the pressure exerted by a distorted coil-spring in its endeavor to assume the position which it holds when at rest, and also broadly new to attach the knife by a loose joint, so that the operator is at liberty to decide at what angle the knife shall enter the wood and is also at liberty to change that angle during any part of the stroke, so that a light or heavy shaving may be taken at will and the danger of breaking the lead is reduced to a minimum.

I am aware that pencil-sharpener have

been made which cut the wood in the direction of its grain; but in no one of them, I believe, is the knife loosely attached, so that its cutting-edge can be raised or lowered 5 without any corresponding movement on the part of the holder, while at the same time the stroke of the knife is also made independently of any movement of the holder. This loose joint gives a freedom and at the same 10 time a delicacy to the stroke of the blade such as have never before been attained in a pencil-sharpener.

The machine is simple, durable, cheap, and remarkably efficient. Though small and compact, it is so strong that the end of the pencil may be cut clear off at one stroke, or through the adaptability of the blade by means of the loose joint where it is attached to the arm of the holder, the operator can go 15 to the other extreme and take a shaving so light as scarcely to remove the paint.

It is obvious that the holder, or that part of the machine which holds the pencil in position and allows it to revolve during the process of sharpening, might be constructed in 20 various other ways—as, for instance, one cylinder gripping the pencil to prevent its forward movement and revolving in another cylinder; but the distorted coil-spring holder is 25 simple, cheap, and effectual, and is preferred by me to any other method of holding the pencil.

In the construction of the knife I am aware 30 that the hole for the attachment to the arm of the holder might be made in some other part of its length, as in the middle, and the knife attached to the holder at that point, the form of the holder being somewhat modified; but neither the action nor the result is so good 35

and there is greater difficulty in securing compactness and in protecting the edge of the knife when not in use, and I prefer in the construction of the machine to attach the knife to the projecting arm of the holder, as shown. 40

What I claim as new, and desire to secure 45 by Letters Patent, is—

1. In a pencil-sharpening machine, a distorted coil-spring holder, substantially as described.

2. The combination of a coil-spring holder 50 and a projecting arm, at the end of which is a suitable bearing for the support and attachment of the knife, all substantially as described.

3. The combination of a distorted coil-spring holder, a projecting arm, and a supporting-coil, as C, all substantially as described. 55

4. The combination of a distorted coil-spring holder, a projecting arm, a supporting-coil, and a catch, as D, all substantially as described. 60

5. In a pencil-sharpening machine, the combination, with a coil-spring holder and a projecting arm, of a knife so attached that the angle at which its cutting-edge moves through 65 the wood of the pencil can be made greater or less at any part of the stroke, all substantially as shown and described.

6. In a pencil-sharpening machine, the combination, with a coil-spring holder, of a projecting arm, a supporting-coil, a catch, and a knife, all substantially as shown and described. 70
